UNITED STATES PATENT OFFICE.

FRANK D. POWELL, OF BOSTON, MASSACHUSETTS, ASSIGNOR TO THE LAMSON COMPANY, OF BOSTON, MASSACHUSETTS, A CORPORATION OF NEW JERSEY.

CARRIER-SYSTEM CHUTE FOR LIGHT ARTICLES.

1,209,883.

Specification of Letters Patent.

Patented Dec. 26, 1916.

Application filed April 29, 1914. Serial No. 835,074.

To all whom it may concern:

Be it known that I, FRANK D. POWELL, a citizen of the United States, residing at Boston, in the county of Suffolk and State 5 of Massachusetts, have invented certain new and useful Improvements in Carrier-System Chutes for Light Articles, of which the following is a specification.

This invention relates to chutes for receiving papers and the like from carrier despatch apparatus and delivering such articles to a suitable receptacle or repository.

In the patent to Pitt, Number 1,084,108, dated January 13, 1914, there is shown a 15 chute of this general character in which a series of chains are suitably suspended to form a cylindric structure, a letter or telegram being delivered to the so formed chute from a carrier which travels upon a wire-line, and the letter or like article descending through the chute after its introduction thereto by gravity.

The present invention may, in certain of its aspects, be regarded as an improvement 25 upon the chute structure shown by Pitt and is intended to so co-act with a sheet of paper or like article which may be descending therethrough as to prevent said article from slipping out edgewise between the chute 30 forming elements. The construction of a chute of this type which shall be free from the objection noted presents certain difficulties which are not at first apparent. In the first place if the chute be made of im- 35 perforate sheet metal or the like a draft is apt to be created therein at times which will prevent the descent of such a light article as, for example, a telegram. In the second place if the chute be made of wire 40 netting of the like the corners of the telegram may insert themselves into the interstices between the wires and thus hold the paper up in the chute.

The chute should preferably be lightly 45 and simply constructed and especially, if it is of any material length, should it be possible to gain access to any article which may have stuck therein, through the walls of the chute.

50 It has been found in practice that even chains are subject to substantially the same objection as that noted against chutes made of wire-netting, and a principal object of the present invention is to provide a chute 55 construction which shall not be subject to

any material extent, to such objections; and one moreover which shall be light in weight and inexpensive to manufacture.

These and other objects of my invention will be hereinafter referred to and the novel 60 combinations of elements by which said objects may be attained will be more particularly set forth in the claims appended hereto.

In the drawing which forms a part here- 65 of and in which like reference characters designate like parts throughout the several views, I have exemplified a preferred construction; but as I am aware of various changes and modifications which may be 70 made herein without departing from the spirit of my invention, I desire to be limited only by the scope of said claims.

Referring to the drawing: Figure 1 is a perspective view of the chute constructed 75 in accordance with the principles of my invention; a portion of a suitable carrier despatch apparatus being shown in connection therewith. Fig. 2 is a view of a preferred carrier, partly in section, and drawn 80 to a larger scale. Fig. 3 is a section through the bottom of the chute, taken on line III—III of Fig. 1.

The carrier herein shown is substantially 85 the same as that shown in the said patent to Pitt, and hence need be but briefly described. It comprises a carrier body 1 mounted on wheels 2 which ride on a line-wire 3.

Below the body or frame 1 is a cylindric 90 receptacle 4 loosely mounted within which, plunger fashion, is mounted a piston-like element 5 which is adapted to slide freely from one end of the carrier to the other by its own momentum when the carrier is 95 brought to a stop. The element 5 is webbed, as best shown in Fig. 2, and this web is upwardly extended through a slot 4' in the cylinder, and carries suitable buffers or bumpers 6, of rubber or the like. 100

A telegram or like article 7 may be rolled up, preferably with the printed side rolled inwardly, and such paper is inserted into the end of the carrier which is nearest to the chute into which such paper is to be ejected; the plunger or piston 5 being pressed back by the insertion of the paper, as shown in Fig. 2. 105

When the carrier is propelled along the wire 3, laden in the manner above described, 110

the forward end of its frame impinges against the loop 8 of a preferably resilient stop 9, which brings the carrier to rest, while the momentum of its plunger 5 ejects 5 the paper sheet 7 into the aperture or mouth 10 of the head 11 of the chute. This head may conveniently be made of wire netting, which may be supported from the bracket 12 to which is connected a wire 3 and also 10 a second or guard wire 13, in a known manner.

Wire 13, it may be here noted, carries a yoke 14 to which are connected the respective ends of the cord 9. The head 11 of the 15 chute has attached thereto a series of preferably flexible elements 15, which depend therefrom, and which elements together with the deflecting balls 16 which are mounted thereon, constitute the body of the open 20 walled chute.

The balls 16 may conveniently be made of wood, and may be fastened to the elements 15 in any suitable manner. The latter are preferably light cords or rope, and while 25 the balls 16 will in the aggregate be sufficiently heavy to normally maintain the desired perpendicularity of the elements 15, I prefer to attach weights 17 to the lower 30 extremities of each of these cords or elements and further to extend these ends through an annulus 18, which may rest upon the weights 17. Thus it will be seen that while the chute as a whole is inexpensive to manufacture, it is nevertheless slightly and 35 furthermore adapted to be folded up into a compact bulk preparatory for shipment.

Within the chute, as shown in Fig. 1, is a telegram which has been ejected from the receptacle 4 of the carrier in a manner above 40 described, and which, it will be noted, has been curled slightly by reason of its having been rolled and inserted into said cylinder.

I have discovered that when a paper has had the edges thereof slightly curled, as 45 shown, it almost invariably tends to descend with the curled edges uppermost; so that when the telegram, for example, has fallen through the chute, it will come to rest upon the repository 18 with its curled edges up 50 and consequently since the printed or typed matter of the telegram is upon this side, it will be immediately ready for inspection without having to turn it over, and moreover practically every one of the so deposited telegrams will be properly faced up, 55 and thereby quite neatly piled. The repository 18, in the present instance, is the corner of the table; but it is evident that any suitable receptacle or repository may be used.

The action of the curled paper in falling 60 through the chute is quite noteworthy, since, if the chute be, for example, five or six feet long, no matter which way the paper may 65 be faced when being introduced into the

aperture 10, said paper will, as stated, practically invariably come to rest with its curled edges uppermost.

If occasion be found to reach into the body of the chute for any reason, the flexible cords 70 15 may be thrust aside wherever desired and the hand introduced at the opening so made.

I particularly desire to call attention to the action of the balls 16 and to the disposition and relative sizes of these balls as compared with the width of the spaces between the cords 15. The balls are preferably staggered and are further preferably sufficiently large to present effective resistance to any paper which may tend to twist out sidewise 80 through the apertures 19 between the cords 15. In the present case the diameter of the balls is about equal to the distance between the centers of adjoining cords; but while it is desirable to thus have the balls so proportioned to the said spaces, they may be made of relatively somewhat less diameter and still effectively accomplish the purpose for which they are provided.

By reason of the fact that they are round 90 and by reason further of the fact that the cords are relatively smooth, these devices present no recesses to the paper sheet in which the corners of the latter might find lodgment.

The utility of the device is strikingly illustrated when one attempts to introduce even a relatively heavy letter, for example, edgewise into the aperture 10 and to even give such an article a twist which one would 100 ordinarily think should be sufficient to cause it to probably pass out through some one of the interstices 19; but upon many repeated trials it will be found that the letter, telegram or the like, will almost invariably be 105 properly retained within the chute until it emerges from the bottom thereof and falls, rightly faced, if its edges be slightly curled, upon the repository or table 18.

Having thus described my invention what 110 I claim is:

1. An open walled chute for paper sheets and the like comprising a head having an opening therein adapted for the reception of said sheets, a series of depending elements having at spaced intervals along the lengths of said elements, but distinct therefrom, means to deflect a falling paper sheet to prevent said sheet from emerging from said chute between said elements, said elements and means being free from recesses which might receive and hold the corners of said paper sheet.

2. An open walled chute for paper sheets and the like comprising a series of substantially vertically disposed weighted elements having at spaced intervals along the lengths of said elements, but distinct from the latter, means to deflect a falling paper sheet to prevent said sheet from emerging from said chute

between said elements, said elements and means being free from recesses which might receive and hold the corners of said paper sheet, means to support said elements and 5 to normally hold them in definite relationship with respect to each other, and a repository at the lower end of said chute, said repository being spaced from at least a portion of the lower end of said chute to permit 10 the removal of a fallen paper sheet while leaving the chute undisturbed.

3. An open walled chute for paper sheets and the like comprising a series of substantially vertically disposed elements having at 15 spaced intervals along the lengths of said

elements balls to deflect a falling paper sheet to prevent said sheet from emerging from said chute between said elements, said elements and balls being free from recesses which might receive and hold the corners 20 of said paper sheet, means to support said elements and to normally hold them in definite relationship with respect to each other.

In testimony whereof I have affixed my signature, in the presence of two witnesses. 25

FRANK D. POWELL.
